US00D751692S

(12) **United States Design Patent**
Rimsa et al.

(10) **Patent No.:** US D751,692 S
(45) **Date of Patent:** ** Mar. 15, 2016

(54) **TISSUE TRANSFER APPARATUS**

(71) Applicant: **LifeCell Corporation**, Branchburg, NJ (US)

(72) Inventors: **Joseph Rimsa**, Palo Alto, CA (US); **Brian J. Domecus**, San Francisco, CA (US)

(73) Assignee: **LifeCell Corporation**, Branchburg, NJ (US)

(**) Term: **15 Years**

(21) Appl. No.: **29/533,766**

(22) Filed: **Jul. 22, 2015**

CLAIM

The ornamental design for a tissue transfer apparatus, as shown and described.

DESCRIPTION

FIG. 1 is a perspective view of a tissue transfer apparatus;

FIG. 2 is a perspective view thereof;

FIG. 3 is a reverse detailed perspective thereof;

FIG. 4 is a side view thereof;

FIG. 5 is a top view thereof;

FIG. 6 is a bottom view thereof;

FIG. 7 is a front end view thereof;

FIG. 8 is a back end view thereof;

FIG. 9 is a right side view thereof; and,

FIG. 10 is a left side view thereof.

All features illustrated in phantom line are expressly disclaimed and form no part of the claimed design.

1 Claim, 8 Drawing Sheets
